UNITED STATES PATENT OFFICE

165,633

PUSH BAR FOR STORE DOORS

Richard Burdick, Dallas, Tex.

Application July 10, 1950, Serial No. 11,042

Term of patent 14 years

(Cl. D10—8)

To all whom it may concern:

Be it known that I, Richard Burdick, a citizen of the United States, residing at the city of Dallas, county of Dallas, State of Texas, have invented a new, original, and ornamental Design for a Push Bar for Store Doors, of which the following is a specification, reference being made to the accompanying drawing, forming a part thereof, in which:

Figure 1 is a top plan view of a push bar for store doors embodying my new design;

Figure 2 is a front elevational view thereof; Figure 3 is a bottom plan view thereof; and Figure 4 is a side elevational view thereof.

I claim:

The ornamental design for a push bar for store doors, substantially as shown.

RICHARD BURDICK.
